UNITED STATES PATENT OFFICE.

CHARLES L. BAILEY, OF ARTHUR BAY, MICHIGAN.

JOINTED PILE.

1,138,924.

Specification of Letters Patent. Patented May 11, 1915.

Application filed June 13, 1914. Serial No. 845,018.

To all whom it may concern:

Be it known that I, CHARLES L. BAILEY, a citizen of the United States, residing at Arthur Bay, in the county of Menominee 5 and State of Michigan, have invented a new and useful Jointed Pile, of which the following is a specification.

The present invention relates to improvements in jointed piles, one object of the invention being the provision of a slip and lock joint for connecting pile sections together, so that the same may be readily locked in place and reinforced at such point while at the same time, being readily disengaged where necessary, there being a flexible connection between the two sections of piles whereby when the same are disconnected, they may be placed alongside of each other, or whereby the upper section may be disconnected and weighted to be submerged during winter so that forming or floating ice will not injure the pile.

A further object of the present invention, is the provision of a jointed pipe, by means 25 of which a pile of any desired length may be secured, by connecting the respective sections together by the joint hereinafter to be described.

With the foregoing and other objects in 30 view which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

In the drawings—Figure 1 is a vertical 40 central sectional view through the adjacent ends of a section of a pile showing the present invention applied. Fig. 2 is a similar view with the sections extended illustrating how the same may be placed side by side 45 without entirely disconnecting the joints.

Fig. 3 is a section on line 3—3 of Fig. 1.

Referring to the drawings, the numeral 1 50 designates one section of a pile, and has disposed thereupon, the cylindrical sleeve 2, the same being held in place by means of the transversely disposed pin or bolt 3. The adjacent section 4 of the pile has its end slightly reduced as at 5 for the reception of the sleeve 6 and the band 6', the limiting 55 shoulder 7 for the lower end 8 of the sleeve 2 is provided upon the section 4, while the

sleeve 6 is provided with the bead or rim 9 which is recessed or slotted as at 10 to receive the lug 11 carried upon the inner side of the sleeve 2 below the end of the pile section 1. It will thus be seen that the lower end of the sleeve 2 will telescopically fit upon the sleeves 6 and 6', the lug 11 being alined with the slot 10, so as to permit the passage of the lug therethrough, the section 1 being turned in either direction so as to place the lug out of alinement with the slot 10 and thus lock the two sections against longitudinal displacement.

A bolt or pin 12 is provided for locking the sleeve 6 in place, while the transverse pin or bolt 12' locks the sleeve 6' in place.

The section 1 is provided with the concentrically disposed cylindrical bore or socket 13 lined at its outer end with a metal sleeve 13', while the section 4 is provided with the concentrically disposed cylindrical socket 14 lined at its outer end with the metal sleeve 14', the said sockets 13 and 14 being disposed to be coaxial when the sections 1 and 4 are together and as shown in Fig. 1. Connected upon the respective pins or bolts 3 and 12', is a chain 15, which when the sections are in the position as shown in Fig. 1, have the slack accommodated within the concentric socket 14, as clearly illustrated. This chain or flexible connection is of sufficient length to permit of the sections 1 and 2 to be separated as shown in Fig. 2 so that they may be placed side by side.

It will thus be seen that with this construction, that the top section may be detached and placed alongside of the upper end of the lower section of the pile and returned to the position and connected as shown in Fig. 1, when necessary.

The chain 15 is provided with a swivel link 16 by means of which one pile section may be rotated without producing a kink in the chain.

What is claimed is:

The combination with two pile sections, of a joint therefor, comprising two telescopic metal sleeves carried by the respective adjacent ends of the sections, one sleeve 105 being provided with a circumferential rim having a slot, a lug carried upon the inner face of the other sleeve for passage through the slot, whereby when one sleeve is rotated within the other, the lug will engage the under side of the rim to prevent longitudinal separation of the sleeves and pile sections,

each of said pile sections being provided with a concentric socket for coaxial disposition, and a flexible connection having its terminals mounted and connected within the sockets intermediate of their ends, said flexible connection being of sufficient length to permit of the separation of the sleeves and the disposition of one section alongside of the other section, the said sockets constituting a receptacle for the slack when the joint is connected.

In testimony that I claim the foregoing as my own, I have hereto affixed my signature in the presence of two witnesses.

CHARLES L. BAILEY.
